UNITED STATES PATENT OFFICE.

ERNEST GERLACH, OF JOHNSTOWN, PENNSYLVANIA.

DESIGN FOR A THIMBLE.

SPECIFICATION forming part of Design No. 27,250, dated June 29, 1897.

Application filed January 19, 1897. Serial No. 619,812. Term of patent 14 years.

To all whom it may concern:

Be it known that I, ERNEST GERLACH, a citizen of the United States, residing at Johnstown, in the county of Cambria and State of Pennsylvania, have invented a new and original Design for a Thimble, of which the following is a specification.

This invention relates to a new and original design for a thimble; and it has for its object to provide a design of this character that shall be both useful and ornamental.

The leading feature of the design resides in a thimble-body formed with an exterior series of closely-arranged concentric annular ridges and depressions, a circular field of circular indentations formed in the outer surface of the crown of the body, and an annular series of radially-disposed serrations formed at the edge of said crown outside of the plane of the circular field of indentations.

In the drawings, Figure 1 is a perspective view of a thimble embodying the herein-described design. Fig. 2 is a top plan view thereof. Fig. 3 is a sectional view.

Referring to the accompanying drawings,

the numeral 1 designates the hollow body of the thimble, which is frusto-conical in shape and is provided at the edge of its wide end with an annular bead 2. Adjacent to the bead 2 the body is formed with a plain annular surface 3, and between said surface and the crown of the body with an exterior series of closely-arranged annular ridges 4, which alternate with corresponding annular depressions. The body 1 is provided in the outer surface of its crown with a circular field of circular indentations 5 and at the edge of the crown with an annular series of radially-disposed serrations 6.

What I claim is—

The design for a thimble herein shown and described.

In testimony that I claim the foregoing as my own I have hereto affixed my signature in the presence of two witnesses.

ERNEST GERLACH.
